UNITED STATES PATENT OFFICE.

JAMES E. SEELEY, OF LOS ANGELES, CALIFORNIA.

X-RAY TUBE.

1,147,125.

Specification of Letters Patent. Patented July 20, 1915.

Application filed March 31, 1913. Serial No. 757,735.

To all whom it may concern:

Be it known that I, JAMES E. SEELEY, a citizen of the United States, residing at Los Angeles, in the county of Los Angeles, State of California, have invented new and useful Improvements in X-Ray Tubes, of which the following is a specification.

This invention relates to a double cathode X-ray tube for use with alternating currents irrespective of their method of production and especially with alternating high frequency currents.

The present invention consists fundamentally in the combination of a pair of cathodes and a single target, in such arrangement that both cathodes may focus on and bombard the target at a single focus point. This invention is effected by an arrangement of both cathodes on the same side of the plane of the impact face of the target; and the arrangement necessitates relatively angular positions of the cathode axes, these axes intersecting at the point of impact on the target, and also practically necessitates the placement of the target at an angle with the plane determined by the cathode axes. These features, and others of more minor importance, accomplish the fundamental object of my invention; that object being to provide a tube capable of operating with alternating currents and having a single focus point on the target.

I will explain in detail in the following specifications, references being had to the accompanying drawings, in which:

Figure 1 is an elevation of my improved X-ray tube. Fig. 2 is a sectional plan thereof.

In the drawings 10 may designate a bulb of any suitable size; and I may provide this bulb with any of the attachments commonly used, such as automatic vacuum maintaining appliances and the like. For clarity of illustration I have only shown herein a plain bulb with the parts necessary to my invention. I provide a pair of elongations or necks 11 each of which contains a cathode 12, the cathode supports and connections 13 extending to the ends of the necks 11 and connecting with terminals 14 at their extremities. The cathodes 12 may be made in any suitable manner; I have shown a standard design.

The cathodes are so placed that their axes (the axes of the cathode rays emanating therefrom) intersect at a certain point, which

point is the focus point 14 on target 15. The cathodes have their discharge faces suitably formed to focus the cathode rays as nearly as possible on the point 14; so that the effect of both cathodes in operation is to form a source of X-rays about the single point 14 of suitably small dimensions to produce concentrated radiation of the X-rays and consequently clear effects produced by them.

It will be seen that the cathodes are both placed on one side of the plane of impact on the target; and the angle between the cathode axes and between them and the plane of the target is determined by consideration of best production of the X-rays and of their unobstructed radiation from the target over a wide field. For instance, it will be seen that the target could be placed at right angles to the line bisecting the plane angle between the cathode axes; but the best X-ray field would then be considerably interrupted by the cathodes themselves unless the cathodes were placed so that there was a very obtuse angle between their axes, and this would diminish the efficiency of production of X-rays. I preferably place the target so that it is not at right angles with the said bisector; and I then place the cathodes in such angular relation as to produce the greatest efficiency of X-ray production in connection with the minimum obstruction of the X-rays by the cathodes themselves. In the tube which I have constructed and used the angles are approximately those shown in the drawings and I have found this arrangement very effective. But I do not wish to limit myself to this particular specific design.

The target 15 may be supported, as at 16 by any suitable means and may have a terminal connection 17, which may be used as a neutral connection. I have shown a simple form of target; a preferred form may be similar to the copper backed target now commonly in use. My combination does not preclude the use of an anode separate from the target; and, as mentioned hereinbefore, my tube may be supplied with appurtenances and accessories as desired.

From the foregoing the use and advantages of my tube will be readily understood. The cathodes will connect into an alternating high potential circuit with the result that they alternately become cathodes or anodes; and a continuous emanation of cath-

ode rays is thus received upon a single point, (or as nearly so as possible) of the target. And in this manner I provide a tube which has the advantage of utilizing alternating currents and giving all the good results of a direct current tube. The nature of the alternating current used is of small consequence. In the current from an ordinary induction coil there is a certain "inverse" current, of duration and amplitude depending upon the coil and interrupter construction. My tube does away with the ordinary ill effects of this inverse current by utilizing it for production of cathode rays which are directed upon the target. Whether or not the current in one direction is equal in duration and amplitude to the opposite current, my target is continuously under impact of cathode rays, as one or the other of the cathodes is always in cathodic action.

Having now described a preferred form of my invention, I claim:

1. In an X-ray tube or the like, a pair of cathodes and a single target, both of the said

cathodes being arranged on one side of the striking plane of said target and focused on a single point thereon, the striking plane of the target being oblique to the plane determined by the rays from the two cathodes.

2. In an X-ray tube or the like, a pair of cathodes and a single target, both of the said cathodes being arranged on one side of the striking plane of said target and focused on a single point thereon, the said striking plane being determined by a line in the plane of the axes from the two cathodes through the impact point on the target and at right angles to the bisector of the angle between said axes and by a line at right angles to and intersecting said first mentioned line making an angle of approximately forty-five degrees with the plane of said axes.

In witness that I claim the foregoing I have hereunto subscribed my name.

JAMES E. SEELEY.
